UNITED STATES PATENT OFFICE.

CHARLES A. KAUFFMAN, OF PITTSBURGH, PENNSYLVANIA.

CALENDAR.

1,299,354.

Specification of Letters Patent.

Patented Apr. 1, 1919.

Application filed July 8, 1918. Serial No. 243,798.

To all whom it may concern:

Be it known that I, CHARLES A. KAUFFMAN, a citizen of the United States, residing at Pittsburgh, in the county of Allegheny and

5 State of Pennsylvania, have invented new and useful Improvements in Calendars, of which the following is a specification.

This invention relates to a calendar and has for its primary object to provide a 10 calendar of such construction that the major portion of the leaves thereof may be used for advertising purposes or for making memorandums.

An object of the invention is to construct 15 the leaves in such a manner that the same may readily fold behind the calendar when a particular month should be in an invisible position, with the advantages that the particular sheet may be preserved.

20 With these and other objects in view the invention will be better understood from the following detailed description taken in connection with the accompanying drawing wherein:

25 Figure 1 is a front view of the calendar. Fig. 2 is a vertical sectional view.

Referring to the drawing which illustrates one form of my invention the numeral 1 designates a plurality of calendar leaves 30 having printed thereon the usual indicia. Each of the leaves is provided with an opening 3 all of which are arranged in registration. The opening of the last leaf is closed by a back sheet 4 which is of a shape to correspond to the calendar leaves. The upper edges of the calendar leaves and back sheet are bound together by a clip 5 that

has stamped therefrom a hook 6. This hook 6 is disposed so as to pass through the opening 3 when a calendar leaf is folded to the 40 rear of the calendar as shown in Fig. 2. Thus it will be seen that the leaves are held in an invisible position without interfering with the support of the calendar with the result that memoranda may be preserved 45 as it is not necessary to tear the leaf from the calendar.

From the foregoing description taken in connection with the accompanying drawing it should be apparent that I provide a calendar of cheap construction by means of 50 which advertising matter may be displayed and memoranda kept from month to month.

Having described my invention, what I claim is:

1. A calendar comprising a plurality of calendar leaves having printed thereon advertising spaces, a clip binding the upper edges of the leaves together and a hook 60 projecting from said clip, each of said leaves being formed with an opening for the passage of said hook when a leaf is folded to the rear.

2. A calendar comprising a plurality of calendar leaves having printed thereon advertising spaces, a back sheet arranged in the rear of said calendar leaves, a clip binding the upper edges of the leaves and back sheet together and a hook projecting from said clip, said leaves being formed with an 65 opening for the passage of said hook when the leaves are folded behind said back sheet. 70

In testimony whereof I affix my signature.

CHARLES A. KAUFFMAN.
